UNITED STATES PATENT OFFICE.

FELIX MERENSKY, OF LEAVENWORTH, KANSAS.

RULING MACHINE.

Application filed January 5, 1926. Serial No. 79,354.

This invention relates broadly to an improved ruling machine of the automatic type, such as is used for mounting of a multiplicity of pens cooperating to draw lines on so-called ruled paper.

While the invention is not limited for use in connection with any particular type of ruling machine, it has been designed with a view to permit it to be applied in the form 10 of an attachment, to a conventional Hickok automatic ruling machine.

In machines of this kind there are a plurality of longitudinally spaced striker beams rockably mounted on the top of the machine 15 and adapted to carry the ruling pens. Under ordinary conditions, cooperating cam means is provided on the striker beams and the machine frame for lifting the beams up at predetermined intervals to render the 20 pens momentarily ineffective. There are times, however, when it is desired to lift these pens up at intervening intervals and to hold them suspended and disengaged from the paper to facilitate operation.

25 The gist of the present invention is to provide a structure, in the form of an attachment, which may be referred to as a striker beam underlift. This is a structure which is mounted on the under part of the conventional frame structure and which is manually operated to permit the striker beams to be lifted up and held in such lifted state for any required length of time.

Briefly, the attachment comprises a rock 35 shaft journaled for angular rotation in appropriate bearing brackets carried by one of the side bars of the frame structure. This rock shaft is operated by a depending push rod which is in turn connected with a pivotally mounted lever. The lever is provided 40 with a foot piece for reception of the feeder's foot. Then, novel means is connected with the rock shaft and extends above it and is engaged with the various striker beams, 45 whereby a depression of the lever will serve to lift the push rod, to rock the shaft, and to simultaneously lift all of the beams to disengage the pens from the paper.

The structural advantages, features, and 50 other results will become apparent from the following description and drawing.

In the accompanying drawing forming a part of this application, and in which like numerals are employed to designate like 55 parts throughout the same:—

Figure 1 is a side view of an incomplete

automatic ruling machine of the type specified showing the improved attachment associated therewith, and the manner in which it operates.

60 Fig. 2 is a side elevation of the attachment removed from the machine.

Fig. 3 is a sectional and elevational view of one of the details of the attachment.

Fig. 4 is an end view of the structure seen 65 in Fig. 3, this figure being in complete elevation.

Fig. 5 is a view taken substantially on the plane of the line 5—5 of Fig. 2.

70 Figure 6 is an enlarged detail view of the foot controlled latch retainer for the operating lever.

Referring to the drawings in detail, the reference character 1 indicates the base portion of a ruling machine of the Hickok type 75 and the reference character 2, see Fig. 1, represents one of the side bars adjacent the top portion of the machine. As before intimated, machines of this kind are provided with a plurality of longitudinally spaced 80 transversely extending striker beams (not shown), which carry the ruling pens. At the end of each beam is a part generally represented by the reference character 3. This may be conveniently referred to as a lifter 85 arm. Cooperating with this arm in each instance is a rotatably mounted driven member 4 which is provided with cam means (not shown) to engage the adjacent portion of the lifter arm for raising it at predetermined intervals. These details form no part 90 of the present invention.

The invention comprises, as before indicated, a plurality of bearing brackets 5. These are mounted on the side bar 2 at the 95 approximate points shown in the drawing. Mounted for rotation in the brackets is a horizontally disposed rock shaft 6. Depending from this rock shaft is a vertically disposed push rod 7, which is pivotally connected at its lower end to a horizontally disposed lever 8. The lever is provided (see Fig. 2) with an apertured ear 9 which is pivoted in any suitable way to the base 1. It will be noted that the outer end of the 100 lever has a depending part 10 and a horizontally extending part 11 terminating in a foot piece 12 adapted for reception of the feeder's foot.

Connected to the opposite end of the lever 110 is a coiled spring 13 which serves to normally maintain the parts of the attachment

in inactive position. Cooperating with the rock shaft, we find a plurality of separate devices generally represented by the reference characters 14. Each device comprises a stem composed of a lower section 15 and an upper section 16, these two sections being pivotally connected together by the joint structure shown in Fig. 2.

Mounted on the frame bar 2 on the inner side are guide brackets 17 through which the sections 16 of the stems are slidable. Attention is now directed to Figs. 3 and 4 wherein it will be seen that the upper stem section 16 terminates in a substantially T-shaped head. Adjustably and slidably connected with this head, is a plate 18 carrying upstanding spaced parallel ears 19 between which an arm 20 is mounted. It will be noted that this arm terminates in a curved extremity 21 which is adapted to cooperate with the aforesaid lifter arm 3, (see Fig. 1). The adjustment of this arm 20 must be very accurate. Therefore I provide a pair of adjusting screws 22 which cooperate therewith and with the plate 18 to change the elevation of the curved extremities. A retaining screw 23 is also provided. The retaining screw, of course, serves to maintain the plate 18 in different adjusted positions on the head 17. Each device 14 is connected with the aforesaid rock shaft 6 through the medium of a crank arm 24 (see Fig. 5). Hence, when the rock shaft is operated, all of the devices will be simultaneously actuated. In order that this result may be obtained, the aforesaid push bar 7 is connected as at 25 with one of the devices as shown in Fig. 2.

Cooperating with the intermediate portion of the lever is a pivotally mounted latch 26 having a counter-weight 27 formed on its bottom. This latch is pivotally mounted upon the base of the frame bar 1, as shown in Fig. 1. This latch is adapted to engage a lug extending at right angles from the inner side of the lever. In addition there is a stop pin 28 to limit the movement of the latch in one direction. Moreover, a link 29 is connected to the intermediate portion of the latch and is then connected with the pivotally mounted operating member 30 which is adapted to be engaged by the operator's foot to release the latch. The latch normally swings to a position to engage the lug and this happens every time the pedal or lever is depressed. This latch arrangement makes it unnecessary to maintain the foot in position on the pedal. It is understood that the device is usually operated by the feeder, but the latch and operating means is not within convenient reach of the feeder's foot. Accordingly the latch and the cooperating parts are controlled by the operator.

The operation of the machine is as follows:

Under ordinary conditions, the attachment does not affect the automatic operation of the ruling machine. However, at the operator's or feeder's discretion, the attachment may be brought into play so that instead of being operated by the automatic means, the striker beams may be raised up at any time by the manual means provided. Under normal conditions, however, this attachment is held in ineffective state by the spring 13. By placing the foot on the pedal 12 and depressing the lever 8, after releasing the latch, the push rod 7 may be raised, to operate the rock shaft 6 and the devices 14. In turn these devices simultaneously lift up the arms 3, and consequently raise the pens on the striker beams from the moving paper. No doubt, those skilled in the art to which the invention relates, will be able to obtain a clear understanding of the invention and the manner of operation. Therefore, a more lengthy description is thought unnecessary.

Minor changes may be made within the field of invention claimed, and may be resorted to if desired.

Having thus described my invention, what I claim as new is:—

1. As a new manufacture, an attachment for an automatic ruling machine adapted for simultaneously raising a plurality of pen equipped striker beams, comprising a rock shaft, means for mounting the rock shaft on said ruling machine, an operating lever, an operating connection between the lever and said rock shaft, and a plurality of separate devices associated with the rock shaft and adapted for cooperation with said striker beams.

2. As a new manufacture, an attachment for an automatic ruling machine adapted for simultaneously raising a plurality of striker beams, comprising a rock shaft, means for mounting the rock shaft on said ruling machine, an operating lever, an operating connection between the lever and the rock shaft, a plurality of separate devices associated with the rock shaft and adapted for cooperation with pen carrying striker beams, each of said devices being adjustably mounted on said machine and including an adjustable arm for engagement with complementary parts of said striker beams.

3. In a structure of the class described, a beam lifting device comprising upper and lower pivotally connected parts forming a lifting stem, the upper part being provided with a head, a U-shaped member slidably mounted on said head, an arm pivotally mounted between the side portions of said member, said arm terminating in a curved lifting finger, and adjusting screws for the pivoted end of the arm.

In testimony whereof I affix my signature.
FELIX MERENSKY.
